the present invention, it is apparent that other preparations may be made without departing from the spirit of the invention. Therefore, I do not wish to be limited to the disclosure set forth, but only by the scope of the appended claims.

I claim:

1. An abrasive suspension consisting of abrasive particles and a medium in which said particles are suspended, said medium being of the group consisting of ethylene glycol dioleate and ethylene glycol mono-oleate.

2. An abrasive suspension consisting of abrasive particles and a medium in which said particles are suspended, said medium being ethylene glycol dioleate.

3. An abrasive suspension consisting of abrasive particles and a medium in which said par-

ticles are suspended, said medium being ethylene glycol mono-oleate.

WILLIS E. BOAK.
